COMPARTMENTED CONTAINER OR TRAY

Arthur Holder, Durham, and Theodore Niedszwecki, Rockfall, Conn., assignors to The Merriam Manufacturing Company, Durham, Conn., a corporation of Connecticut

Application December 17, 1946, Serial No. 716,848

1 Claim. (Cl. 220—21)

1

The present invention relates to improvements in containers or trays and relates more particularly to compartmented containers or trays, i. e., containers which are subdivided into a plurality of compartments to accommodate and to hold separate a plurality of items such, for instance, as coins, mechanical parts, postage stamps, etc.

The compartmented containers of the present invention, like the prior art, include a container-body, a trough-shaped bottom-member provided with transverse slots, and a plurality of partition-plates respectively installed in the said slots.

The prior compartmented containers above referred to have required that each individual partition-plate be secured to the container-body independently of the bottom-member and at relatively-great expense for assembly.

Furthermore, in the construction of the prior art above referred to, suitable fixtures have been required in order to locate the various partition-plates in their appropriate positions before fastening the same in place in the container-body.

The main object of the present invention is to provide a superior compartmented container of the character above referred to, in which the trough-shaped bottom-member will itself serve to retain the plurality of partition-plates in place within the container-body and without requiring the individual securing of the said partition-plates to the container-body.

Another object of the present invention is to provide a superior compartmented-tray construction wherein the assembly cost of its component parts is materially reduced.

A further object of the present invention is to provide a superior compartmented container of the general character above referred to and having its component parts so constructed and arranged that the plurality of partition-plates may be first assembled with the trough-shaped bottom-member to be thereby held in the desired relative locations prior to the installation of the unit comprising the said bottom-member and the plurality of partition-plates in the container-body.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a perspective view of one form of a

2

compartmented container or tray constructed in accordance with the present invention;

Fig. 2 is a broken longitudinal sectional view thereof taken on the line 2—2 of Fig. 1, but on a larger scale;

Fig. 3 is a transverse sectional view taken on the line 3—3 of Fig. 1, but on a larger scale;

Fig. 4 is a similar view, but taken on the line 4—4 of Fig. 1;

10 Fig. 5 is a broken detail sectional view of the area indicated at 5 in Fig. 4, but on a larger scale;

Fig. 6 is a perspective view of one form of the trough-shaped bottom-member suitable for carrying out the present invention;

15 Fig. 7 is a perspective view of one of the partition-plates of the preceding figures;

Fig. 8 is a perspective view of the assembly comprising the bottom-member and a plurality of partition-plates, viewing the same partly from the underside thereof; and

20 Fig. 9 is a transverse sectional view similar to Fig. 3, but illustrating an alternative form of bottom-member and partition-plate.

25 There is illustrated in Figs. 1 to 8 inclusive, a compartmented container of tray-like form which includes in the main, a rectangular tray-like container-body generally designated by the reference character 10, a trough-shaped bottom-member generally designated by the reference character 11, and a plurality of partition-plates generally designated by the reference character 12. All of the said parts may be formed of sheet metal or other suitable sheet material.

30 The container-body 10, in the instance shown, comprises a bottom-wall 13, complementary side-walls 14—14 and complementary end-walls 15—15. The side-walls 14—14 and end-walls 15—15 above referred to are all integral with the bottom-wall 13 and the respective opposite ends of the said side-walls are bent inwardly over the outer faces of the end-walls 15—15 to provide attaching-flanges 16 which may be spot-welded or otherwise secured to the adjacent portion of an end-wall 15 to stiffen the structure. Preferably, 35 the upper edges of each of the end-walls 15—15 are reversely bent as at 17 to further stiffen the structure and to provide a smooth rounded surface.

40 45 The bottom-member 11 before referred to, has the upper edges of its respective opposite side-walls 14—14 bent downwardly to provide each thereof with one of two guard-flanges 18—18 which fit over the upper edges of the side-walls 14—14 of the container-body 10 and engage with

50 55 The bottom-member 11 before referred to, has the upper edges of its respective opposite side-walls 14—14 bent downwardly to provide each thereof with one of two guard-flanges 18—18 which fit over the upper edges of the side-walls 14—14 of the container-body 10 and engage with

the outer surfaces thereof, in the manner especially well shown in Fig. 5.

The bottom-member 11 is formed with five (more or less) transverse slots 19 substantially equidistantly spaced from each other and all having their ends terminating short of the adjacent edges of the bottom-member, for purposes as will hereinafter appear. The length of the trough-like bottom-member 11 is such as to fit snugly between the opposite end-walls 15-15 of the container-body 10.

Preferably, the trough-like bottom-member 11 is so preformed as to have an appreciable tendency to draw its respective opposite side edges toward each other beyond the positions in which they are held when engaged with the upper edges of the side-walls 14-14 of the container-body 10, all for purposes as will more fully hereinafter appear.

Each of the partition-plates 12 above referred to is adapted to extend through a given one of the slots 19 of the bottom-member and is of a length such as to snugly fit between the respective opposite side-walls 14-14 of the container-body 10. The height of the partition-plates 12 is preferably such as to bring the upper edge of each thereof substantially flush with the upper surfaces of the respective opposite edges of the trough-like bottom-member 11 when the latter and the said partition-plates are installed in the container-body 10, in the manner illustrated in the drawings.

Each of the partition-plates 12 is formed in its respective opposite ends, adjacent its upper edge, with one of two corresponding notches generally designated by the reference characters 20-20. The bottom of each of the said notches provides an upwardly-facing retaining-abutment 21 which engages with the material at the ends of the slots 19 of the bottom-member 11 to hold the partition-plate against upward displacement. Preferably and as shown, one wall of each of the notches 20 is outwardly sloped to substantially conform to the shape of the adjacent upper surface of the edge-portions of the bottom-member 11 to thus provide what may be aptly termed a "holding" surface or abutment 22.

In assembling the compartmented container above described, it is preferred to first insert the partition-plates 12 respectively in the transverse slots 19 in the container-body from the underside thereof, after slightly springing the respective opposite edge-portions of the said bottom-member outwardly, to permit such insertion. When the spreading tension upon the bottom-member 11 is relaxed after the insertion of the partition-plates, the said edge-portions will spring inwardly and engage the upper surfaces thereof with the holding-surfaces or -abutments 22 of the respective partition-plates and thus hold the partition-plates in assembled relationship with the said bottom-member, in the manner illustrated in Fig. 8.

The unit comprising the bottom-wall 11 and the five (more or less) partition-plates 12, may now be set down into the container-body 10 so that the parts assume the positions in which they are shown in Figs. 1 to 5 inclusive.

The entire unit of Fig. 8 may now be held in assembled relationship with respect to the container-body 10 by two spot-welds 23-23 (or other suitable fastening-means) serving to rigidly attach the transversely-central portion of the bottom-member 11 to the bottom-wall 13 of the container-body 10, as is indicated in Fig. 2.

If desired and for very severe usage, the guard-flanges 18 of the bottom-member 11 may be suitably secured to the container-body by means of spot-welds 24-24, either in addition to the spot-welds 23-23 or in lieu thereof.

From the foregoing, it will be apparent that by means of the construction and arrangement of parts shown, the respective partition-plates 12 do not require individual securement directly to the container-body 10 but are held in place by the simple act of fastening the bottom-member 11 to the said container-body.

Furthermore, it will be apparent that the assembly cost is further reduced by being able to first assemble the partition-plates 12 with the bottom-member 11 to provide the multi-part unit illustrated in Fig. 8, and then inserting this unit into the container-body 10 without requiring the aid of other spacing-means.

In Fig. 9 is illustrated a slightly modified form of bottom-member which is generally designated by the reference character 25, together with a slightly modified partition-plate generally designated by the reference character 26.

Instead of being of curved form in cross section like the bottom-member 11, the bottom-member 25 is of angular form in cross section though still of trough-like form. The partition-plate 26 is formed adjacent its respective upper corners with notches generally designated by the reference characters 27-27 of less acute form than the notches 20 before described. Each of the said notches has a substantially-horizontal bottom-wall providing an upwardly-facing retaining-abutment 28 engaged by the end-walls of the transverse slot 29 through which the given partition-plate 26 extends, and in the manner illustrated in Fig. 9.

The remaining wall of each of the notches 27-27 is sloped outwardly to conform to and engage with the adjacent surface of the edge-portions of the bottom-member 25 so as to provide a holding-abutment 30 functioning in the same manner as the holding-abutment 22 before described.

The angular or paneled body-member 25 is formed at its opposite edges with down-turned guard-flanges 31-31 which are adapted to fit over the upper edges of the respective side-walls 14-14 of a container-body 10, in the same manner as that described in connection with the construction of the figures preceding Fig. 9.

The bottom-member 25 and a series of partition-plates such as 26 may be assembled in the same manner as that described in connection with the construction of Figs. 1 to 8 inclusive and may, in turn, be installed in the container-body 10 and held therein in the same manner as has been previously described.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claim are intended to be embraced therein.

We claim:

A compartmented container including in combination: a container-body having a bottom wall and a pair of spaced-apart lateral walls; a concavo-convex bottom-member performed of resilient sheet material, said bottom-member having oppositely-disposed upper edges, each of

which is provided with a guard-flange extending downwardly throughout the length of said upper edge and hooked over the upper edge of the corresponding lateral wall of said container-body to hold said bottom-member therein, said concavo-convex bottom-member having a plurality of slots extending transversely thereof, each of said slots having a downwardly-facing substantially-straight transverse end-wall at the respective opposite ends thereof positioned below the corresponding upper edges of said bottom-member; and a plurality of partition-plates respectively installed in the slots of said bottom-member so as to project beyond both the upper and lower faces thereof, each of said partition-plates being provided with a notch adjacent its respective opposite ends, each of said notches having a substantially-straight bottom edge constituting an upwardly-facing retaining-abutment arranged substantially opposite the corresponding downwardly-facing transverse end-wall of the slot in which the partition-plate is installed to lockingly engage therewith, whereby each of the said partition-plates is held positively by the said concavo-convex bottom-mem-

ber against upward displacement with respect to said container-body.
